US0D1026221S

(12) **United States Design Patent** (10) Patent No.: **US D1,026,221 S**
(45) Date of Patent: ** May 7, 2024

- (54) **CONNECTOR FOR A RESPIRATORY SYSTEM CONDUIT**
(71) Applicant: **Fisher & Paykel Healthcare Limited**, Auckland (NZ)
(72) Inventors: **Rachel Nicole Mosen**, Auckland (NZ); **Andrew James Webb**, Auckland (NZ); **Hugo Max Treherne James**, Auckland (NZ); **Bruce Gordon Holyoake**, Auckland (NZ); **Andrew William White**, Auckland (NZ); **Clodagh Mary Moran**, Auckland (NZ); **Graeme Matthew Smith**, Auckland (NZ); **Craig Karl White**, Auckland (NZ); **Jojo Santos Badenas**, Auckland (NZ)
(73) Assignee: **Fisher & Paykel Healthcare Limited**, Auckland (NZ)
(**) Term: **15 Years**
(21) Appl. No.: **29/820,533**
(22) Filed: **Dec. 22, 2021**

CLAIM

The ornamental design for a connector for a respiratory system conduit, as shown and described.

DESCRIPTION

FIG. 1 is a front perspective view of a connector for a respiratory system conduit which embodies our design.

FIG. 2 is a right side view thereof.

FIG. 3 is a front view thereof.

FIG. 4 is a left side view thereof.

FIG. 5 is a rear view thereof.

FIG. 6 is a bottom view thereof.

FIG. 7 is a top view thereof.

FIG. 8 is a front perspective view of a second embodiment of a connector for a respiratory system conduit which embodies our design.

FIG. 9 is a right side view thereof.

FIG. 10 is a front view thereof.

FIG. 11 is a left side view thereof.

FIG. 12 is a rear view thereof.

FIG. 13 is a bottom view thereof; and,

FIG. 14 is a top view thereof.

The broken lines in the drawings illustrate portions of the connector for a respiratory system conduit which form no part of the claimed design. The inventors and applicant contemplate embodiments that claim the presently disclaimed subject matter.

The surface shading is an artefact of filing in the United States of America and does not necessarily form part of the claimed design. The inventors and applicant contemplate removal of a portion or all of the surface shading.

The references to “left”, “right”, “front”, “rear”, “top” and “bottom” in the figure descriptions are not meant to require certain in-use orientation; the connector for a respiratory system conduit according to the claimed design may be used on any orientation.
